WEIGHT SUPPORT AND LIFTING DEVICE

Joy P. Arnold, Des Moines, Iowa

Application December 29, 1949, Serial No. 135,657

11 Claims. (Cl. 27-28)

1

My invention relates to a weight supporting and lifting device and is more particularly designed for use by morticians in the handling and moving of corpses while preparing them for burial.

After a body has been received by a mortuary it must be moved and lifted many times before it has been prepared for interment and placed in the casket ready for the administration of the last rites and the actual burial. During the process of embalming, cleaning, dressing and the many other tasks required in this respect the moving, lifting and handling is generally done by physical labor and obviously requires the services of more than one person. The actual work, however, in preparing the body can generally be performed by one person, except when lifting and moving is necessary. Often a good deal of time and effort is lost if this additional help is not always available at just the proper time. Also, in many smaller funeral establishments the added cost for this type of assistance is an important item.

It is therefore an object of my invention to provide a corpse supporting and lifting device for use by morticians that can easily and quickly be operated by one person.

A further object of this invention is to provide a supporting and lifting device of the above class that is easily and quickly adjustable to accommodate bodies of different diameters.

A still further object of this device is to provide a body lifting device for use by morticians than can be used to lift a corpse from a table, cot or the like and to lower it into a casket and that after the body is resting therein this device may be easily removed without moving the body. In this respect it is also particularly designed to permit its removal without being hampered or restricted by the close confines of the casket walls.

Still another object of this invention is to provide a weight supporting and lifting device of the above classes that is easily movable to different locations within the room in which it is installed.

A still further object of this device is to provide a corpse supporting and lifting means for use by morticians that may be mounted on an overhead crane and thereby does not take up floor space in the room where it is used.

These and other objects will be apparent to those skilled in the art.

My invention consists in the construction, arrangement, and combination of the various parts of the device, whereby the objects contemplated are attained as hereinafter more fully set forth, pointed out in my claims, and illustrated in the accompanying drawings, in which:

Fig. 1 is a perspective view of this device with the dotted lines indicating a corpse being supported thereby.

2

Fig. 2 is a longitudinal section view of this device taken on the line 2-2 of Fig. 1 with a cut away portion at the top to more fully illustrate the construction thereat and with the broken lines in the lower part illustrating the adjustability of the lifting arms.

Fig. 3 is a side view of one pair of lifting arms of this device showing one of the arms engaging a body, indicated by dotted lines, with said arm secured to the lifting means and the other arm of the pair detached from the lifting means and being maneuvered into position under the body, and

Fig. 4 is a cross-sectional view of a portion of 15 a pair of lifting arms taken from the line 4-4 of Fig. 2.

Referring to the drawings I show my device mounted on an overhead traveling crane. No invention is claimed in this respect as such cranes have long been in use for moving lifting devices carrying heavy weights. The two spaced parallel runways 10 are positioned overhead and may be secured in any suitable manner such as to the ceiling 11 of a room or on terminal supports or the like. The crane preferably consists of two parallel spaced beam members 12 disposed transversely to the runways and rollably mounted thereon. Obviously, the longitudinal plane of the runways will be determined by the particular location so that the crane will be able to reach all places where its use will be needed. The numeral 13 designates a plurality of V-shaped support brackets secured between and to the beams 12 in longitudinal spaced relation, as 25 shown in Fig. 1. Preferably one such bracket 13 is at each end of the beams 12 and the length of the beams will determine the number of intermediate brackets required. The numeral 14 designates a horizontal elongated rotatable shaft 30 member supported by the brackets 13 in any suitable manner such as the bearing members 15 secured to each of the brackets, as shown in Fig. 1. One end of the shaft 14 communicates with a gear box 16 which provides the means for rotating the shaft when the crank handle 17 is manually operated. The gear box is mounted at one 35 end of the crane structure in any suitable manner.

On the shaft 14 I have secured a plurality of 40 spool members 18 disposed in longitudinal spaced relation, as shown in Fig. 1. The numeral 19 designates a plurality of flexible strap members, respectively, detachably secured to and wound about each of the spools 18. On the free end of 45 each strap 19 there is secured a metal ring member 27. Obviously, the direction of rotation of the shaft 14 will cause the straps 19 to wind or unwind thereon and the gear box 16 will maintain the shaft at any position where its rotation is stopped.

The lifting arms which are used with the above

structure are the novel elements in this invention and I will now describe them. The numeral 20 designates a pair of complementary like elongated bar members each having its respective end portions 21 and 22 bent at substantially a right angle and in the same direction. The bar portion intermediate the bend points on each bar is curved outwardly so that when the bars are disposed as shown in Fig. 1 they provide a stirrup-like appearance. Thus arranged the bottom end portions 22 of the arms 20 will provide a supporting surface for a weight and the outwardly bulging sides are designed to conform generally to the curvature of a corpse for which this device is adapted.

Each of the upper end portions 21 of the arms 20 is provided with an elongated slot 23 that communicates with the free end thereof, as shown in Fig. 4. The numeral 24 designates a horizontal support bar member having an upwardly extending centrally positioned hook member 25. The top end portions 21 of each arm 20 are detachably laterally slidably secured to the underside of the bar 24 by any suitable means such as the bolt and wing nuts 26, as shown in Fig. 2 and Fig. 4. As illustrated in Fig. 4 this is done by passing the bolt 26 through end holes (not shown) in the bar 24 and the slots 23. In this way, the arms 20 are laterally extendable as shown by the broken lines in Fig. 2 and may be secured in any extended position by the wing nuts 26.

In operation this device has several advantages. In the drawings I show three pairs of like lifting arms arranged so that the weight of a body 28 can be evenly distributed and balanced. Each pair of arms can be individually positioned about a body without having to move the body so that one person can easily operate this device. This may be done in two different ways. For smaller bodies the lifting arms 20 can be extended, as shown in Fig. 2, so that the bottom end portions 22 can be placed on opposite sides thereof and then manually pushed toward each other to the desired position. With the wing nuts 26 then tightened the arms will support the weight and will not slip.

Should the body be large, however, or in a narrow place, either or both of the arms 20 can be quickly detached from the bar 24, as shown in Fig. 3 and manually maneuvered into position without having to move or lift the body. Once the lower arm portions 22 are in place, the upper end portions 21 can be secured as previously described.

To release the arms 20 the process of securing them is merely reversed. When a body has been lowered by this device into a casket, the detachability of the arms 20 is especially useful. In such a situation the body is, of course, within the close confines of the casket and having been dressed and prepared for the last rites at which it will be viewed by former friends and family the less it is disturbed, the less work and time is required to properly adjust it. Consequently, after the body is resting in and supported by the casket it is difficult to release the arms by spreading them laterally because of the closeness of the side walls. However, with this device it is only necessary to detach the arms from the support bar and manually rotate each arm so that the bottom end portions slide out from under the body to a point where it can be vertically lifted out without disturbing the body or casket lining in any way.

I have shown this device mounted on an overhead traveling crane and the advantage in this is that it can easily be moved about where needed, is always available and yet does not occupy floor space. This is often an important consideration when mortuaries are crowded for space. However, it is pointed out that this device could also be mounted on a supporting structure that itself is mounted on wheels and movable about on the floor.

Some changes may be made in the construction and arrangement of my weight support and lifting device without departing from the real spirit and purpose of my invention, and it is my intention to cover by my claims, any modified forms of structure or use of mechanical equivalents which may be reasonably included within their scope.

I claim:

1. In a weight supporting and lifting device for use by morticians in the handling of corpses, a lifting arm comprising, a pair of complementary like bar members each having its respective end portions bent at an angle and in the same direction and substantially parallel to each other; said bar members disposed opposite each other to provide a stirrup-like appearance, a slot provided in the upper bent portion of each of said bar members, a bar; each of said first mentioned bar members detachably secured by means of said slots to said bar and said bar secured to a means by which it can be raised and lowered.
2. In a weight supporting and lifting device for use by morticians in the handling of corpses, a lifting arm comprising, a pair of complementary like bar members each having its respective end portions bent at an angle and in the same direction and substantially parallel to each other and with the bar portions intermediate said bend points curved outwardly; said bar members disposed opposite each other to provide a stirrup-like appearance, an elongated slot provided in the upper bent portion of each bar member; each of said slots communicating with the free end of its respective bar member, a bar, each of said first mentioned bar members detachably slidably secured by means of said respective slots to said bar and said bar secured to a means by which it can be raised and lowered.
3. In a weight supporting and lifting device for use by morticians in the handling of corpses, a lifting arm comprising, a pair of complementary like bar members each having its respective end portions bent at an angle and in the same direction and parallel to each other; said bar members disposed opposite each other to provide a stirrup-like appearance with the bent end portions forming the bottom of said lifting arm having their free ends closely adjacent to each other whereby they are adapted to extend under substantially all of the corpse to be lifted, a slot provided in the upper bent portion of each of said bar members, a bar; each of said first mentioned bar members detachably secured by means of said slots to said bar and said bar secured to a means by which it can be raised and lowered.
4. In a weight supporting and lifting device for use by morticians in the handling of corpses, a lifting arm comprising, a pair of complementary like bar members each having its respective end portions bent at an angle and in the same direction and parallel to each other and with the bar portions intermediate said bend points curved outwardly; said bar members disposed opposite each other to provide a stirrup-like appearance

with the bent end portions forming the bottom of said lifting arm having their free ends closely adjacent to each other whereby they are adapted to extend under substantially all of the corpse to be lifted, an elongated slot provided in the upper bent portion of each bar member; each of said slots communicating with the free end of its respective bar member, a bar, each of said first mentioned bar members detachably slidably secured by means of said slots to said bar and said bar secured to a means by which it can be raised and lowered.

5. In a weight supporting and lifting device for use by morticians in the handling of corpses, a lifting arm comprising, a pair of complementary like bar members each having its respective end portions bent at an angle and in the same direction and parallel to each other; said bar members disposed opposite each other to provide a stirrup-like appearance with the bent end portions forming the bottom of said lifting arm having their free ends closely adjacent to each other whereby they are adapted to extend under substantially all of the corpse to be lifted, a slot provided in the upper bent portion of each of said bar members, each of said first mentioned bar members detachably secured by means of said slots to a means by which it can be raised and lowered.

6. In a weight supporting and lifting device for use by morticians in the handling of corpses, a lifting arm comprising, a pair of complementary like bar members each having its respective end portions bent at an angle and in the same direction and parallel to each other; said bar members disposed opposite each other to provide a stirrup-like appearance with the bent end portions forming the bottom of said lifting arm having their free ends closely adjacent to each other whereby they are adapted to extend under substantially all of the corpse to be lifted, a slot provided in the upper bent portion of each of said bar members, each of said bar members detachably secured by means of said slots to a means by which it can be raised and lowered, each bar member being individually and separately movable toward or away from the other bar member, and selectively removable from and rotatable on the means by which it is raised and lowered.

7. In a weight supporting and lifting device for use by morticians in the handling of corpses, a lifting arm comprising, a pair of complementary like bar members each having its respective end portions bent at an angle and in the same direction and parallel to each other and with the bar portions intermediate said bend points curved outwardly; said bar members disposed opposite each other to provide a stirrup-like appearance adapted to conform to the curvature of the corpse to be lifted with the bent end portions forming the bottom of said lifting arm having their free ends closely adjacent to each other whereby they extend under substantially all of the corpse, a slot provided in the upper bent portion of each of said bar members, a third bar member, each of said first mentioned bar members detachably secured by means of said slots to said third bar member, each of said first mentioned bar members being individually and separately movable toward or away from the other bar member, and selectively removable from and rotatable on said third bar member.

8. In a weight lifting and supporting device, an overhead support member, a retractable lifting means on said support member, an improved grappling member operably associated with said lifting means, characterized by a pair of complementary like bar members each having its respective end portions bent at an angle and in the same direction and parallel to each other; said bar members disposed opposite each other to provide a stirrup-like appearance, a slot provided in the upper bent portion of each of said bar members; each of said bar members detachably secured by means of said slots to said lifting means.

9. In a weight lifting and supporting device, an overhead support member, a lifting means depending from said support member, a bar member detachably secured to the free end of said lifting means, a lifting arm comprising, a pair of complementary like bar members each having its respective end portions bent at an angle and in the same direction and parallel to each other; said second mentioned bar members disposed opposite each other to provide a stirrup-like appearance, a slot provided in the upper bent portion of each of said second mentioned bar members, each of said second mentioned bar members detachably laterally slidably secured by means of said slots to said first bar member.

10. In a device of the class described, a horizontal bar member designed to be supported by suitable means, a curved arm bar member having its respective end portions bent at an angle in the same direction and parallel to each other, a slot in the upper bent portion of said curved arm bar member having its upper end portion slidably mounted by means of said slot to one end portion of said horizontal bar member, and a second curved arm bar member of like construction as the first having its upper end portion similarly slidably mounted to the other end portion of said horizontal bar member so that the upper and lower free end portions of the respective curved bar members are oppositely disposed.

11. In a device of the class described, a horizontal bar member designed to be supported by suitable means, a curved arm bar member having its respective end portions bent at an angle in the same direction and parallel to each other, a slot in the upper bent portion of said curved arm bar member having its upper end portion slidably and rotatably mounted by means of said slot to one end portion of said horizontal bar member, and a second curved arm bar member of like construction as the first having its upper end portion similarly slidably and rotatably mounted to the other end portion of said horizontal bar member so that the upper and lower free end portions of the respective curved bar members are oppositely disposed.

JOY P. ARNOLD.
